UNITED STATES PATENT OFFICE.

LUCIUS R. ROSEBROOK, OF OSKALOOSA, IOWA, ASSIGNOR TO HARRY H. ROSEBROOK, OF DES MOINES, IOWA, AND FREEMAN D. ROSEBROOK, OF CHICAGO, ILLINOIS.

BRIDGE FOR ABUTTING TRACK RAILS.

Application filed March 12, 1924. Serial No. 698,668.

To all whom it may concern:

Be it known that I, LUCIUS R. ROSEBROOK, a citizen of the United States of America, and resident of Oskaloosa, Mahaska County, Iowa, have invented a new and useful 5 Bridge for Abutting Track Rails, of which the following is a specification.

The object of this invention is to provide 10 improved means for bridging the joints between abutting track rails, and particularly between a rigid rail and a rail mounted on a movable object such as a scale or turntable.

A further object of this invention is to 15 provide improved means for transferring the weight of rolling stock from track rails to rails located on movable members such as track scales or turntables, and avoiding shock and damage to such movable members.

My invention consists in the construction, 20 arrangement and combination of elements hereinafter set forth, pointed out in the claims and illustrated by the accompanying drawing, in which—

Figure 1 is a plan view illustrating one 25 method of mounting my improved bridge or approach relative to a track rail and a scale rail. Figure 2 is a side elevation of the same, partly in section. Figure 3 is a cross-section on the line 3—3 of Figure 2.

Figure 4 is a side elevation, partly in section, showing a modified method of mounting the bridge or approach.

Figure 5 is a view similar to Figure 4, showing a further modified form.

Figure 6 is a plan view illustrating a 35 method of mounting the bridge or approach slidably, adapting it to use in connection with a rotatable member or turntable.

This invention relates to and is an improvement on the devices illustrated, described and claimed in Letters Patent of the 40 United States granted to me May 17, 1921, Number 1,378,425, for approach for track-scales.

In the construction of the devices as 45 shown particularly in Figures 1, 2 and 3, the numeral 10 designates a portion of a scale platform, with which are associated suitable weighing devices (not shown) for use in weighing railway rolling stock. On the platform 10 are mounted scale rails 11, one of which is shown, in alinement with but 50 preferably slightly spaced from track rails 12 of a railway track, carried by cross ties 13 in the usual way. A bed or foundation

14 of concrete, or a coping, preferably underlies certain ties 13 nearest the scale, or assists in supporting the ends of the track rails 12 in any suitable manner. A spring 60 plate 15 has one end portion mounted on and fixed to a cross tie 13 spaced from the end of the track rail 12, preferably the second tie from the end of said rail, being fixed to said tie by spikes 16, and may also be supported by a flanged chair plate 17 extending beneath said rail. The spring plate 15 extends

65 parallel with and adjacent to the rail 12 and across the joint between said rail and the scale rail 11, overlapping upon the platform 10 of the scale but not being fixed thereto, said spring plate being mounted along side the inner faces of said rails, and on or in connection with both rails forming the track. A chair plate 18 is provided and is 70 mounted on the scale platform 10 and a similar chair plate 19 is mounted on the cross tie 13 nearest thereto, adjacent the joint between the rails 11, 12 beneath said rails and conjunctively secured therewith to the platform and tie, respectively, and the free end portion of the spring plate 15 extends loosely 75 across said chair plates. An approach or bridge member 20 overlies and is secured by bolts 21 or the like to the free end portion of the spring plate 15 and lies in a position 80 immediately above the chair plates 18, 19 and extending across and adjacent the joint between the rails 11, 12. The chair plates 18, 19 are formed on their inner longitudinal 85 margins with vertical flanges 18', 19' respectively, parallel with and close to that margin of the spring plate 15 farthest from the track rails 11, 12, and said flanges overlap upon the base portion of the bridge or 90 approach member 20 and serve to prevent movement of said member laterally away from the rails. The bridge or approach member 20 is formed with a portion which extends loosely between the base and head 95 of the rails 11 and 12, and thus said member is confined and limited as to movement, being permitted a limited vertical movement with the free end of the spring plate 15 but no lateral or longitudinal movement, because 100 of its attachment to the spring plate and its juxtaposition to the rail and to the flanges 18', 19'. The bridge or approach member 20 is formed with an inner lip 22 or ridge, which is substantially parallel with and 105 spaced from the rails. Between the lip or 110

ridge 22 and the rails 11, 12 the approach or bridge member 20 is formed with a flangeway or groove 23 which is formed on a convex arc indicated substantially by dotted lines in Figure 2. The groove or flangeway 23 extends from end to end of the member 20 and is adapted to receive the flange of a railway car wheel passing along the rails 11, 12. End portions of the groove or flangeway 23 are sufficiently low that a car wheel is carried by the rails 11 or 12 in the usual manner, the face of the wheel resting on the ball of the rail; but the curvature and rise of such flangeway is such that in its central portion the flange of the car wheel contacts the approach or bridge member and the wheel is lifted from the rail. This transfer of the weight of the car wheel is effected before it reaches the joint between the rails, so that the weight of the load is transferred from the track rail to the approach member and from it to the scale rail. As the car wheel moves along the approach or bridge member the spring plate 15 yields and presses downwardly upon the scale platform and gradually lowers such platform, within its range of movement, so that by the time the flange of the wheel has passed to the downwardly inclined portion of the flangeway and the wheel comes into contact with the scale rail, said platform, and the weighing devices then having been depressed into weighing position relative to the load thereon. This transfer of the weight prevents sudden shocks and jars to the weighing apparatus, injury to the knife edges and springs and also crawling of the scale rails which often results from sudden impact of a load upon the scale. The bridge or approach device holds the scale platform firmly until the car trucks are on the scale and then it releases the scale so that it is free for the weighing operation, the resilience of the spring plate 15 permitting a downward movement below its normal horizontal plane, at its free end which overhangs the scale platform.

At times it may be desirable to employ the bridge or approach member without the spring plate, mounting it so that it is free to move vertically to a limited extent, or to tilt or oscillate slightly on a transverse axis as the weight is transferred. When so used the chair plates may be employed to limit vertical movement of the bridge or approach member and to prevent lateral movement, but additional means must be employed to prevent longitudinal movement, since its connection to the spring plate is done away with. In Figures 4 and 5 I have shown two modifications for so using the device. In Figure 4 the bridge or approach member 20^a is formed in its central portion with a downwardly projecting lug or stop 24 engaging rather loosely between the spaced

chair plates 18, 19, thus permitting some rocking movement of said member as a car wheel passes over it, but preventing any material longitudinal movement; lateral movement thereof being prevented, as before, by flanges of the chair plates. In Figure 5 a similar arrangement is provided except that the approach or bridge member 20^b does not have any projections, and it is confined against longitudinal movement by end flanges 18^a, 19^a on the outer ends of the respective chair plates 18^a and 19^a.

In Figure 6 I have shown an adaptation of my invention to use in connection with a member which is not only capable of a slight vertical movement, as is a track scale, but also adapted for lateral or rotary motion; in other words a railway turntable. For such use it is necessary to provide means for withdrawing the bridge or approach members from their normal position across the rail joints, at such times as it is desired to rotate the turntable. In this view, the turntable proper is indicated by the numeral 25, which carries rails 26, 26 extending substantially diametrically thereof and adapted to cooperate in alinement or abutting relation with track rails 27, 27, a plurality of which are usually arranged at a given location in positions radially of the axis of the turntable. A pair of bridge or approach members 20 are provided to bridge the joints between the rails 26 and 27, said members preferably being slidably mounted in and relative to chair plates 18, 19 similar to those shown in Figures 1, 2 and 3, provided at their inner margins with longitudinal flanges 18', 19' designed to guide said members in their sliding movement and to prevent lateral movement thereof. These chair plates are mounted respectively on the turntable 25 and on the ties such as 13 rigidly located adjacent thereto and supporting the track rails 27, and are arranged beneath the rails 26 and 27 and conjunctively secured therewith to the respective supports. Any desired means may be employed for sliding the bridge or approach members 20 in their seats and withdrawing them from their position extending across the rail joints. In this instance I have shown a rock shaft 28 journaled in bearings 29 carried by the turntable 25, said shaft being provided with a lever 30 adapted for its manual operation, and at its ends formed with cranks 31, 32 pivotally connected by links 33, 34 with the respective bridge or approach members 20. The lever 30 and cranks 31, 32 are adapted for movement through arcs of about one hundred eighty degrees, from a horizontal position on one side of the rock shaft to horizontal position on the opposite side, which movement results in the desired shifting of the members 20 to or from their normal positions bridging the joints be-

tween the abutting track rails. As the members 20 and their operating devices are located on the turntable, they may be caused to cooperate with any set of track rails 5 such as 27 with which the turntable rails 26 are caused to aline, and they serve a similar function to that previously described in transferring the weight of rolling stock, and more particularly locomotives, to and 10 from the turntable without undue shocks and jars to the mechanism. Any other suitable means may be employed for shifting the members 20, or for rocking the shaft 28 in case it is employed.

15 I claim as my invention—

1. A bridge for abutting rigid and movable track rails, comprising chair plates mounted beneath said rails adjacent the joint therebetween, and a bridge member 20 mounted on said chair plates parallel with said rails and extending across the joint, said bridge member being formed with a grooved flangeway parallel with the rails adapted to receive flanges of car wheels, said 25 chair plates being formed with stops to limit lateral movement of the bridge member away from the rails.

2. A bridge for the joint between a movable and a rigid track rail, comprising chair plates mounted beneath said rails adjacent said joint, a spring plate anchored adjacent said rigid rail and extending loosely alongside the movable rail, and a bridge member mounted on said spring plate and extending across said joint, said bridge member being formed with a grooved flangeway parallel with the rails adapted to receive flanges of car wheels, said chair plates being formed with flanges parallel with said rails to prevent lateral movement of the bridge member.

3. A bridge for the joint between a movable and a rigid track rail, comprising chair plates mounted beneath said rails adjacent 45 said joint, and a bridge member mounted on said chair plates and extending across said joint, said bridge member being formed with a grooved flangeway parallel with the rails

adapted to receive flanges of car wheels, said chair plates being formed with flanges 50 parallel with and spaced from the rails to prevent lateral movement of the bridge member, together with means to prevent longitudinal movement of the bridge member.

55 4. A bridge for the joint between a rigid and a movable track rail, comprising a chair plate mounted beneath the end portion of each rail adjacent the joint, each chair plate being formed with a marginal flange parallel with and spaced from the rail, and a bridge member mounted on said chair plates and held by said flanges against lateral movement away from said rails, said bridge member being formed with a grooved 60 flangeway parallel with the rails and crossing the joint, said bridge member being free to move to a limited extent with said movable rail.

65 5. A bridge for the joint between a rigid and a movable track rail, comprising a chair plate mounted beneath the end portion of each rail adjacent the joint, each chair plate being formed with a marginal flange spaced from the rail, a bridge member mounted on 70 said chair plates and adapted to extend across said joint, and means for sliding said bridge member longitudinally to withdraw it from the location of said joint.

75 6. A bridge for the joint between a rigid and a movable track rail, comprising a chair plate mounted beneath the end portion of each rail adjacent the joint, each chair plate being formed with a marginal flange spaced from the rail, a bridge member mounted on 80 said chair plates and adapted to extend across said joint, a rock shaft formed with cranks, and a link pivotally connecting said bridge member to a crank of said rock shaft 85 to move said bridge member longitudinally 90 relative to the rail joint when said rock shaft is operated.

Signed at Oskaloosa, in the county of Mahaska and State of Iowa, this 14th day of February, 1924.

LUCIUS R. ROSEBROOK.
